UNITED STATES PATENT OFFICE.

DANIEL M. WEBSTER, OF MANSFIELD, OHIO, ASSIGNOR TO THE AULTMAN & TAYLOR MACHINERY COMPANY, OF MANSFIELD, OHIO, A CORPORATION OF OHIO.

STEAM-BOILER.

SPECIFICATION forming part of Letters Patent No. 742,938, dated November 3, 1903.

Application filed December 3, 1902. Serial No. 133,795. (No model.)

To all whom it may concern:

Be it known that I, DANIEL M. WEBSTER, of Mansfield, in the county of Richland and State of Ohio, have invented a new and useful Improvement in Steam-Boilers, of which the following is a full, clear, and exact description, reference being had to the accompanying drawings, forming part of this specification, in which—

10 Figure 1 is a side elevation, partially in section, of a steam-boiler constructed in accordance with my invention; and Fig. 2 is a horizontal section on the line II II of Fig. 1.

In the drawings, 2 represents the steam and 15 water drum, 3 the mud-drum, and 4 the connecting-tubes, of a water-tube boiler.

5 is the furnace-chamber, 6 the brick setting or shell of the boiler, and 7 the outlet-flue extending through the upper drum, which 20 is preferably made of annular form, the bank of tubes being correspondingly annular in their arrangement.

8 is a circulating-pipe which extends outside the brick shell from the water-space of 25 the upper drum to the mud-drum outside of the tube-chamber, so that, being in a cooler part, it may induce a circulation up through the water-tubes.

For the purpose of superheating the steam 30 obtained from the boiler I form in the upper drum an annular jacket 9, surrounding the outlet-flue 7 above the water-line, and provide it with a steam-delivery pipe 10, extending to the exterior of the boiler, and with a 35 steam-inlet opening 11, preferably separated from the outlet by a partition 12, so that the steam entering at the inlet will travel around the jacket to the outlet and, being subjected in its passage to the heat communicated 40 through the material of the steam-drum from the hot gases, will be highly superheated thereby. This device is important, because by superheating the steam in the efficient manner which it renders possible the utility 45 of the boiler is increased and desirable results are secured. This may be applied not only to boilers in which the outlet-flue extends through the steam-drum, but to boilers in which the hot gases pass on the exterior of

the drum; but in such case the steam-jacket 50 should be applied to the outer shell.

I have also provided my boiler with means for preventing priming, by which I mean the carrying of water out with the steam by reason of the rapid circulation of the water 55 through the tubes, which in some cases is so violent as to cause to a serious extent the evil just mentioned. For this purpose I place in the steam-drum a submerged perforated or grid-like plate 13, situated below the water-line, preferably only a few inches below the same. This plate may extend entirely across the steam-drum or it may be placed only in that part of the drum which is opposite the ends of the tubes in which the most violent 60 ebullition occurs. Even when the water is oily, which generally causes the most violent ebullition, the presence of the perforated baffle-plate is sufficient to check the foaming and it renders it harmless. 70

In order to prevent unequal heating of the tubes of the boiler and to cause the gases to pass through among the rear tubes to as great an extent as among the front tubes, I employ in addition to the ordinary baffle- 75 plates 15, which are set in the space in the center of the bank of tubes, a vertical deflecting-plate 16, which extends upwardly from the upper baffle and partially around the circumference thereof, terminating sufficiently far from the upper end of the bank of tubes to leave an intervening space for passage of some of the gases. This deflector serves to obstruct somewhat the path of the gases at the front portion of the bank of tubes 80 and deflects the current toward the rear of the setting, and in this way I am enabled to secure an almost perfect distribution of the gases among the tubes of the boiler. In practice I prefer to extend the deflector about 85 half-way around the baffle-plate, as I find that this gives the most desirable results under ordinary conditions; but its shape and size may be varied by the skilled mechanic.

I claim—

1. A steam-boiler having an annular bank of tubes, a baffle-plate set in the central space and a deflector-plate extending upwardly 95

from the baffle and partially around the circumference thereof; substantially as described.

2. A steam-boiler having an annular bank of tubes, a baffle-plate set in the central space and a deflector-plate extending upwardly from the baffle and partially around the circumference thereof, said deflector-plate being set near the top of the bank of tubes and terminating sufficiently far from the end of the bank of tubes to leave an intervening space for the passage of the gases; substantially as described.

3. A steam-boiler having an annular bank of tubes and a deflector at the upper portion

thereof, said deflector obstructing the gas-passage at one part of the setting more than the others; substantially as described.

4. A steam-boiler having an annular bank of tubes, and a deflector at the upper portion thereof, said deflector obstructing the gas-passage at the front of the setting more than at the rear; substantially as described.

In testimony whereof I have hereunto set my hand.

DANIEL M. WEBSTER.
